DRINKING GLASS OR THE LIKE

Melvin H. Levi, New York, N. Y.

Application October 3, 1952, Serial No. 21,681

Term of patent 14 years

(Cl. D36—8)

To all whom it may concern:

Be it known that I, Melvin H. Levi, a citizen of the United States of America, and a resident of New York city, county of Queens, and State of New York, have invented a new, original, and ornamental Design for Drinking Glass or the like, of which the following is a specification, reference being had to the accompanying drawing forming part thereof, in which:

Fig. 1 is a front view of a drinking glass, or the like, embodying my new design;

Fig. 2 is a central vertical section of the drinking glass of Fig. 1; and,

Fig. 3 is a plan view of the drinking glass of Fig. 1.

I claim:

The ornamental design for a drinking glass, or the like, as shown

MELVIN H. LEVI.
